CLAIM

We claim the ornamental design for a footwear arch support, as shown and described.

DESCRIPTION

FIG. 1 is a side elevation of a footwear arch support, embodying our new design;

FIG. 2 is an opposite side elevation view thereof;

FIG. 3 is top plan view thereof;

FIG. 4 is a bottom plan view thereof;

FIG. 5 is a front elevation view thereof;

FIG. 6 is a rear elevation view thereof;

FIG. 7 is a top perspective view thereof; and,

FIG. 8 is an opposite top perspective view thereof.

The broken lines shown are included for the purpose of illustrating portions of the article that form no part of the claimed design.
